UNITED STATES PATENT OFFICE.

HOWARD S. FOLKER, OF MILL VALLEY, CALIFORNIA, ASSIGNOR TO THE NATIONAL SAFETY APPLIANCE COMPANY, OF SAN FRANCISCO, CALIFORNIA.

RAILWAY TRAIN CONTROL.

Application filed October 27, 1920. Serial No. 419,907.

To all whom it may concern:

Be it known that I, HOWARD S. FOLKER, a citizen of the United States, and a resident of Mill Valley, county of Marin, State of California, have invented certain new and useful Improvements in Railway Train Controls, of which the following is a specification.

This invention relates to improvements in train control mechanism for use on railways in which there is provided magnetic means fixed on the roadbed co-operating with magnetic means carried by the railway locomotive or other railway vehicle, by means of which when one magnet is in the field of the other the pneumatic train stop is operated to cause the application of the brakes and give an audible signal to the engineer.

The above statement describes generally that which is common between the present invention and the inventions disclosed in Patents No. 1,322,418 granted to me November 18, 1919, and No. 1,334,520 granted March 23rd, 1920, to me and Foree Chittenden, as joint inventors.

The particular objects of the present invention are to provide a structure and installation which is an improvement over the structures of the above mentioned patents to the end that it is simplified, more compact, yet positive in operation, reliable and low in construction, installation and maintenance costs.

Another object is to provide a structure in which light moving parts may be utilized, thus giving higher speed of operation, to provide means in the duplex control valve by which the operating air may be strained to exclude dust and moisture and to also provide a duplex valve which is devoid of springs, the presence of which are well known causes of weakness and uncertain or faulty operation.

Another object of the invention is to provide improved means for effecting the application of the brakes in the event that the inductor planes on the duplex control valve carried by the locomotive or tender should become broken.

Another object of the invention is to provide means for protection against over strong magnets in the duplex control valve struc-

ture and to provide such a structure as to operate effectively when the train is going in either direction, or the track magnet is placed to lie in either direction.

Another object is to improve the mechanical structure of the train stop and to provide an improved double heading release cock to be operated by the engineer after the train has been brought to a stop in order to place the stop mechanism in condition for further automatic operation.

Another object of the invention is to provide a device which is capable of operation even when the vehicle is moving at extremely high speed and is but momentarily in cooperation with the control magnet or other operating means.

Another object is to provide a construction composed of units assembled for venting the train air pipe (brake pipe) or other operating mechanism either on the forward or rear part of the train or vehicle.

Other objects will appear from the subjoined specification and claims when read in connection with the accompanying drawings, in which:

Fig. 1 is a plan diagrammatically shown as a section of a railway track showing adjoining blocks and disclosing a track magnet and its controlling means and also the duplex control valve unit which is carried by the vehicle and which co-operates with the track magnet.

Fig. 2 is a side elevation of the same.

Fig. 3 is a view partly broken away and in side elevation of a portion of a locomotive and also of a portion of the track and the control apparatus, showing the relative positions of the apparatus carried by the locomotive and supported by the track.

Figs. 4, 5 and 6 are details in plan and elevation of the permanent track magnet and the electro-control magnet which is mounted adjacent thereto.

Fig. 7 is a diagrammatic view with parts in section and other parts broken away illustrating the complete control unit carried by the train and connected to the engineer's control valve and brake pipe.

Fig. 8 is a top plan view of the improved duplex control valve structure with inductor planes.

Fig. 9 is a sectional view taken on the line 9—9 of Fig. 8.

Fig. 9^a is a vertical section of the valve supporting fitting.

Fig. 9^b is a plan of the same.

Fig. 10 is a section on line 10—10 of Fig. 8.

Fig. 11 is a sectional view of a train stop showing its normal running position.

Fig. 12 is a longitudinal section of the train stop showing the parts in the position they assume when the brakes are automatically applied.

Fig. 12^a is a section on line 12^a—12^a of Fig. 12, shown in elevated position.

Fig. 13 is a side elevation of the double heading release cock.

Fig. 14 is a plan of the same.

Fig. 15 is a section on line 15—15 of Fig. 13.

Fig. 16 illustrates a local circuit at each magnet location.

In the interest of clearness the specification will be divided into three parts. In the first part there will be described the general assemblage of the various elements of the installation, their relative positions and the effect of one upon the other; in the second part, each mechanism will be treated serially and its operation described, and in the third part, the operation of the system as a whole will be clearly set forth.

This invention is designed as an adjunct to fixed block or interlocking signal systems; is constructed for interconnection with same, and its operation is controlled as in such visible signal systems. Automatic stop operation is caused whenever a condition is produced which would cause a standard automatic semaphore signal to assume the stop position and should the engineer fail to obey the fixed signal indication.

The invention is also operable when the signals are actuated manually, in this instance suitable circuits along the track being provided to control the operation of the electro-control magnet.

The track apparatus consists of a permanent magnet mounted on the ties in the center of the track, its length parallelling the rails, and its upper surface being preferably about one inch below the upper surface of the rails. An electromagnet control unit is positioned below and across the poles of the permanent magnet and is of superior power when energized. Its control is through the standard track and line circuits of any standard automatic signal system, current from a standard signal battery being supplied to the electromagnet control unit through a local control circuit for clear movements only, and only while the train is passing through a short local track section. The control is provided as desired, for either

magnetic field of the permanent magnet is in condition for automatic-stop operation, and it is rendered effective only for clear movements by energizing the electromagnet control unit.

Referring first to the track installation shown in Figs. 1 to 6 and 16, inclusive, 10 represents the supporting rails of a suitable railroad mounted on ties 11, the same being divided into blocks A, B, C, etc., by the insulations 12. In each block, as illustrated, there is positioned a short distance below the rails, a polarized permanent track magnet 13 preferably of the horseshoe type and also an electro-control magnet 14 in which there is a core 15 and a coil 16, and extended pole pieces 17 and 18 which preferably, because of the naturally cramped position of the mechanism, flare outwardly and upwardly in order to be operatively associated with the opposite poles of the track magnet 13. The respective pole pieces of the track magnet and of the electro-control magnet are marked N and S to distinguish their polarities, as shown. The polarized permanent track magnet is secured to the ties in any suitable way and the electro-control magnet is secured to the track magnet in order to hold the two in operative position, one with respect to the other, and this structure is normally covered in any suitable way.

The general structure and operation of the polarized permanent track magnet and the electro-control magnet is disclosed in Patent No. 1,334,531 granted to me and D. M. Bidstrup on March 23, 1920, in which the electro-control magnet is positioned adjacent the poles of the permanent track magnet with the poles reversed with respect to the poles of the permanent magnet to provide a means for deflecting the field of the permanent magnet and during such deflection, distorting the magnetism of said permanent magnet, thus permitting free passage thereover of the locomotive and train.

The locomotive apparatus, as will herein-after more particularly appear, consists of the magneto pneumatic control valves,—for receiving stop actuation from the permanent magnet on track,—and a pneumatic stop valve,—for causing automatic brake application,—the latter with a valve for release and double-heading. The magneto pneumatic control valves are hung in tandem below the locomotive or tender and they are provided with inductor planes hung in parallel, which planes are provided with flat pole faces adjusted to ride over the poles of the permanent track magnet at clearance of 5" to 6" more or less. The polarity of one magneto control valve is fixed opposite to that of the other magneto control valve, ensuring stop actuation regardless of locomotive heading, that is, regardless whether the train is proceeding in

one direction or in a direction opposite, netic force flowing from one pair of duplex magnets to the other, so that the holding force on the armature will not be reduced too much. Mounted inside the valve housing are two magneto pneumatic valves 70 V, one seated at each end thereof. The structure of each of these valves is the same, but the duplex magnets M and M' are arranged in pairs, one pair having a polarity opposite to that of the other pair. The duplex magnets M and M' are securely clamped to the pole pieces 28 by magnet binders 32 and cap screws 33, as clearly shown in the drawing. The cap screws 33 pass through the magnet binder 32 which is recessed to fit the ends of the magnets and hold them in spaced relation to each other, as clearly shown in Figs. 9 and 10. Operation of this stop valve is controlled by the magneto control valves and when operated, brake application is made, either service or emergency, as provided for needs of train service. The valve for release and double-heading provides for release of brakes after an automatic-stop application has been made and also for cutting out automatic-stop apparatus on following engines of same train.

These pieces of apparatus constitute what is known as the engine equipment and are connected by suitable pipes or air ducts leading from the main reservoir to the brake pipe and in the operation of which the air respectively enters into and is vented from the brake pipe.

Duplex control valve.

In general the duplex control valve F is encased in a cast brass housing and is suspended from a connection flange 20 to which it is bolted by suitable screwthreaded bolts b. The flange 20 is suspended by rigid hangers 21 from the center sills S of the locomotive tender, or in any other suitable place conditions may make desirable. The duplex control valve is carried in spaced relation above the tracks or running rails of the roadbed and extends in a line parallel to the rails.

The cast brass housing 22 is provided with four outwardly extending lugs 23 through which pass the screw-threaded bolts b which secure the valve housing to the connection flange 20 from which it is suspended. On either side of the valve housing and integral with it are four extending hubs or lugs 24, each of which is of the same construction and form and only one need therefore be described. These lugs (see Fig. 9) are provided with axial openings in each of which is mounted a core or pole piece 25 of high permeability, such as Norway iron. These cores or pole pieces are screw-threaded at each end, as at 26 and 27, the inner ends 26 being engaged by the screwthreads into the magnet pole pieces 28 and the external ends of these cores or pole pieces are fastened by suitable screwthreaded nuts 29 to the cast iron inductor planes P which are also secured to the lugs of the housing by cap screws 30 and lock washers 31. On the ends of the extension hubs or lugs 24 of the duplex magnet casing are fitted non-magnetic bushings 34 to sufficiently reduce the mag-

two points to respectively secure thereto the cap screws 33 for the magnet binder 32 and the screw threaded end 26 of the core 25. The pole piece extensions or cores 25 are secured in fixed relation in the lugs 24 by means of set screws 34 and lock nuts 35.

It is preferable to construct the valve parts of bronze and all chambers and recesses of the interior thereof are concentric with the external surface of the valve stem.

A valve stem guide bushing 41 fits snugly in the recess in the top of the valve fitting 40, and seated diametrically opposite each other and extended into the upper face of the valve are two round cavities into which pole piece dowels 42 are fitted. A small brass guide pin 43 is securely fastened in the center of one of each pair of the pole piece dowels and extends upwardly therefrom to serve as a guide for the armature 45, which armature seats or rests upon the top faces of the pole piece dowels 42.

The armature 45 is provided with a small hole 44 through one end thereof into which the aforesaid brass pin 43 extends and is loosely fitted so that the armature may freely move in a vertical direction. This pin is also for the purpose of preventing the armature from turning on the valve stem and away from the pole piece dowels 42. The bronze valve stem 46 is preferably round in cross section and one end is made smaller in diameter than the other, the smaller end being screwthreaded at 47 to receive the acorn nut 48.

The armature rests on a washer 49 which fits over the small end of the valve stem 46. By means of the acorn nut the elements are secured together and yet the valve stem 46 is permitted to turn freely on the armature.

In assembling this structure, the valve fitting 40 is inserted into the bottom of the housing 22 through the opening 40'. The pole piece dowels pass through and snugly fit in holes 51 in the under side of the magnet pole pieces 28. The combined valve

stem 46 with the attached armature 45 is inserted into the valve fitting 40 and the armature is attracted and held fast on the top face of the pole piece dowels 42 by the 5 magnetic poles of the magnets M.

The valve stem 46 extends down through the valve stem guide bushing 41 through the chamber 60 and the bottom end of the stem which forms the valve proper is flush 10 with the top of the chamber 733. A flexible valve seat 62 preferably of leather is securely clamped in the chamber 733 by a valve seat bushing 63. In the center of the leather valve seat is a hole 65, the area 15 of which is less than the area of the face of the valve proper which in this instance is the lower end of the valve stem 46. The area of the valve surface which is exposed to the air pressure is thus reduced, which 20 enables the magnet M to maintain the armature 45 in engagement with the pole pieces and hold the valve end against the side of the flexible valve seat 62, which, being flexible, is forced by the air pressure against 25 the end of the valve, thus maintaining a tight seal thereof at all times when the valve is seated.

A cap 70 is constructed of cast brass and is secured to the under side of the duplex control valve by suitable bolts b' and sealed by means of a gasket g and this cap is provided with air passages to be hereinafter described.

Extending from the top face or flange portions of the cap and integral with it is a cylinder 72 forming a chamber 73 which contains a strainer 74, the strainer being soldered to a screw threaded plug 75 which plug is provided with a port 76 to strain any water or dirt the strainer may collect, this port being formed by means of an axial hole drilled partly through the plug in the center thereof extending into a hole drilled radially through the shoulder of the plug. The 45 strainer is fitted through an opening in the bottom of the cap, said opening being screw-threaded to receive the plug 75. When the plug is screwed up tight into position with its shoulder abutting against the bottom of the cap 70, it forms an air tight closure and in order to drain the dirt and water from the strainer the plug must be unscrewed a few 50 turns to expose the radial hole in its shoulder.

55 A strainer nipple 77 is fastened into the top of the cylindrical portion of the cap by suitable screwthreads as at 78. The bottom end of the nipple 77 is enlarged and is cone shaped and fits snugly into the top of the strainer 74. This nipple is provided with an air passage 79 extending axially therethrough. The pressure fluid passes through passage 79 into and through strainer 74 into a surrounding chamber 73 from whence it 60 passes through passages 80 to valves V. The 65

strainer nipple 77 extends up through an opening in the bottom of the valve housing 22, the top of the nipple being flush with the top of the valve housing cover 20.

The casing of the duplex control valve is 70 hollow and forms a protecting housing for the magneto pneumatic valve structure and the hollow chamber is open to atmosphere through the ports 735 (Fig. 9) so that when the valve stem 46 is raised, air pressure passing through the aperture 65 in the flexible valve seat 62 will be vented to atmosphere through the ports 735.

Train stop.

80 The part marked 100 (see Figs. 11 and 12) is the main connection flange into which all the pipe connections lead and it is provided with a flat surface on one side to which the main body 110 is bolted with suitable bolts. 85 A gasket 130 is inserted therebetween so as to make an air tight joint, thus ensuring against leakage between the several air passages. The valve body 110 contains a valve 140 which for clearness will be designated 90 as the non-release valve. This valve 140 is located between the brake pipe 150 and the usual engineer's brake valve C which is of the flat rotary type having many ports, the interior construction of which it is not necessary to particularly describe herein as it is 95 already understood in this art.

The valve body 110 is provided with chambers 170 and 180 separated by a wall 190 in which a valve seat 200 is provided, said valve seat being so situated as to cooperate with the non-release valve 140, which valve is secured to the valve stem 210. The bottom end of said valve stem 210 projects through a perforated web 220 into the cylindrical 105 chamber 230. To the lower end of the valve stem 210 is removably secured a flat disc valve 240 by means of a screw 250 and said disc valve is provided with leather or any other suitable packing material 260, as 110 shown.

A piston 300 operates in the cylindrical chamber 230, the walls of which are integrally cast with the walls of the valve body 110. The valve 240 which is secured to the 115 lower end of the valve stem 210 is normally closed, the upward pressure beneath the piston 300 and the compression spring 320 co-operating to secure a firm seat of the valve upon the valve seat 310 formed in the top 120 portion of the piston 300. The piston 300 is spool shaped, as clearly shown in the drawings (Figs. 11 and 12) being turned from a solid piece of metal and is provided with a plurality of grooves into which are fitted 125 metallic packing rings 390 for the purpose of making air tight joints between the piston and cylinder walls at each end of the piston, all as shown in the drawings and as well understood.

A port 330 is provided in the wall of the cylinder 230 at a point midway between each end flange of said piston 300, which port is the brake pipe service exhaust port.

- 5 The piston 300 as above stated, is specially shaped and consists therefore of three parts. The central part 350 is provided with flanges at each end, each forming between them a concentric or annular chamber 410 which is in communication with the port 330 at all times. The valve seat 310 for the valve 240 is centrally located on the top of the piston and it is concentric with the perpendicular passage or port 420, the lower 10 end of which is closed and connects at intermediate points with radial ports 430 which communicate with the chamber 410.

- The main reservoir is so connected that air will flow through the main connection 20 flange 100 by suitable pipes and fittings 500, thence through the restricted port 510 of fixed capacity, into the passage 520 and into the perpendicular passage 530, thence into the chamber 540 building up pressure 25 therein. The lower portion of the chamber 540 is closed by a cylinder head 304 which is provided with a chamber 301 which communicates with the port 530 by means of a passageway 302. The chamber is closed by 30 a screwthreaded support 307 which engages with screwthreads on the wall of the chamber, the said support provided with a perforation 303 in the center thereof which forms communication between the chambers 35 540 and 301. A plug 306 passes through a hole in the bottom of the cylinder head and is provided with a screwthreaded cavity in which fits the screwthreaded shank 308 which extends from the valve 309 and from 40 which extends upwardly the projection 308 having a diameter slightly smaller than the diameter of the hole 303.

The plug 306 is locked in place by a suitable seal as well understood, which obviously must be broken before the hand knob 305, which is suitably secured to the central plug 306, can be turned. In the event that the pipe supply to the chamber 540 should become broken, or for any other reason the 50 supply of fluid pressure to said chamber should be stopped, the piston 300 will become inoperative and I am therefore enabled by the construction just described to quickly replace the piston and the parts 55 operated thereby into normal position by turning the hand knob 305, thus lifting the stud 308 upwards into the chamber 540 and forcing the piston and co-working parts into normal position regardless of the air 60 pressure, the stud 308 being suitably splined against turning. When the stud is moved into its upward position the valve 309 closes the port 303 thus preventing waste of air to atmosphere in the event that the pipe 65 718 is broken and making the brakes opera-

tive regardless of the fluid pressure in the stop apparatus.

Double heading release cock.

The double heading release cock 600 (see Figs. 7, 13 and 14) is a substantially rectangular bronze casting with two bosses 601 and 602, one at the top and one at the bottom of the main casting. The cock 600 is divided into two chambers 603 and 604 between which chambers is a slot 605 to receive a lever handle 606. Tapered plug cocks 607 and 608 are entered through the bosses 601 and 602 respectively, the small ends of the plug cocks being flattened at 80 609 and 610, both entering an opening 611 in the lever handle 606, so that they may turn together when the lever is operated. Pressing against the larger ends of the plug cocks 607 and 608 and encased in the bosses 85 601 and 602 are springs 612 and 613 for the purpose of holding the plug cocks 607 and 608 firmly into their seats. The bosses 601 and 602 are screwthreaded and fitting therein are two screw plugs 614, 615 which hold 90 the springs in place and cause them to exert pressure upon the plugs 607 and 608.

The entrances to the chambers 603 and 604 are suitably screwthreaded at 603' and 604' for connection by means of suitable 95 pipes and fittings 714 and 718 which connect respectively to the engineer's brake valve C and to the train stop D.

In the chamber 604 is a port 620 so arranged that with the lever 606 in the double 100 heading release position and the air passage 718 closed, any pressure building up in the air passage 730 will, through leakage, vent to atmosphere through the port 620. The double heading release cock 600 is so located 105 on the engine that in order to gain access to it the engineer must dismount from his cab, and it is also used to cut out operation of the train stop apparatus when the air 110 control is cut off from the following engine, or engines when more than one engine is used on the train. As will be clearly understood from the drawing, the double heading release cock 600 has two air passages, one of which is interposed between 115 the pipe 718 and the pipe 730 to the magneto pneumatic duplex control valve F and the other 714 is connected by suitable pipes and vents to a special cock which attaches to the engineer's brake valve C and exhausts 120 to the atmosphere.

The double heading release cock is so constructed that when it is in running position and the air passage 730 which supplies the magneto pneumatic valve F is 125 open, the air passage 714 is closed by means of plug cock 607; conversely, when the passage 730 is closed the air passage 714 is open and the double heading release cock is thus in double heading and released 130

position. The plug cocks 607 and 608 are attached to a common level handle 606 and operate simultaneously.

In order to permit restoration to normal position of the duplex control valve units after exhausting to the air supply, the air passage 730 must be cut off and this is done by turning the lever handle 606 to released position. When the control valve units have been restored to normal position, the air supply must be renewed and this is done by returning the lever handle 606 to running position. Failure to do so will leave the brakes still in non-released condition as the air is exhausting through the air passage 714 and plug cock 607.

Operation.

The track is divided as usual into a series of blocks insulated from each other. A single permanent track magnet associated with an electro magnet control unit of opposite polarity are installed at the entrance of each block. The track magnet acting alone is capable of controlling the operation of the train stopping means carried by the train every time a train passes over the magnet since it has a polarity opposite to that of one of the valve magnets. The electro magnet control unit, however, is energized whenever its circuit is closed by a train closing the track and line circuits of a system to provide clear signals and thus acts to divert the free field of the track magnet and thereby prevents the track magnet from causing the train stopping mechanism of the train to operate. The installation of the electro magnet control unit is such that it will be energized on the approach of a train when the block ahead is clear or unoccupied, and its circuit will not be closed by the approach of a train when the block ahead is occupied, thereby permitting the permanent track magnet to act upon the train stopping mechanism. The reason the electro magnet control unit acts upon the track magnet to divert its field is due to the fact that the former is stronger than the permanent track magnet and its polarity is opposite thereto. The electro magnet control unit may be operated in several ways, one by use of a relay, the circuit of which is controlled by the block ahead, or it may be operated by reason of the fact that it is in circuit with the rails of the block. In the latter instance, however, the battery would have to be very strong and therefore to prevent excessive use of the battery it is preferably in circuit with a short track section of several rail lengths and this circuit is closed upon the entrance of the first wheels therein, the wheels and axle acting as a switch in the circuit.

As has been stated above the particular means for controlling the track magnet is not of this invention, the track magnet being controlled in any approved manner. All that is necessary to do is to set the track magnet in condition for affecting the magnet valves of the train when the train should be stopped. A simple and effective installation is shown in Fig. 16 in which the rails 10 of the railway are divided into track sections A, B and C, by insulations 12 which electrically insulate one section from another. At one end of each section there is connected a suitable electric battery, provided to energize a relay which is connected at the opposite end of the section. It will be noted that as a pair of wheels of a railway car or locomotive passes into a section the relay in that section will be de-energized, due to the electric current from the battery being shunted through the wheels and axle, which form a path of less resistance than the relay coils.

It is to be noted (Fig. 16) that the line and track relays are normally energized, and that local relay S, controlling the track electro-magnet, is normally de-energized, the circuit controlling this relay being open.

Assuming that a train is passing through the installation with the track ahead of the train unoccupied and all apparatus in normal position; when the train enters track section B track relay B⁴ is shunted, and opens a contact point in one branch of the circuit controlling local relay S.

As the train enters track section A, track relay A⁴ is shunted, and a circuit is completed to energize relay S as follows: From positive side of battery, wire 801 to point of relay A⁴; from point of relay A⁴, wire 802, to point of relay 500, wire 803, to coils of relay S, and wire 804, to the negative side of battery. Relay S is therefore energized, and the circuit to the track electro-magnet control 14 is completed through the front point of relay S as follows: From positive side of battery, wire 805 to point of relay S, wire 806, coil of electro-control magnet 14, wire 807 to negative side of battery. This results in diverting the free field of the track permanent magnet thus permitting the train to proceed without interference. As soon as the train passes into section C relay C⁴ is shunted, de-energizing relay C⁴. When the points of relay C⁴ open, the controlling line circuit is broken and line relay 500 is de-energized. The opening of the points of line relay 500 opens one branch of the circuit controlling local relay S, thus opening the circuit to the electro-magnet control, preventing waste of current.

With the track ahead clear this is a normal operation for either direction (but re-

lays C⁴ and 500 operate instead of B⁴ as given above) and it is typical of all indication points for traffic in both directions.

Assuming that track section C is occupied, and a train approaches from B, track relay C⁴ and line relay 500 being open both branches of the circuit controlling relay S are broken, and this relay cannot be energized. Hence current will not be supplied to the track electro-magnet control unit to divert the field of the track permanent magnet; consequently, an automatic operation of the locomotive apparatus will follow.

When a train passes over the track magnet in stopping condition the field of the track magnet acts upon the inductor planes of the duplex control valve F which causes a reversal of polarity in one of the armatures thereof and thus permits the release of the armature from the poles installed as heretofore described in the duplex control valve and thereby permits the opening of the valve therein because of the air pressure normally exerted thereon, which action results in the stopping of the train.

Each magneto pneumatic control valve comprises a permanent duplex horseshoe magnet with pole pieces extending outwardly and downwardly and terminating in broad flat inductor planes and an armature normally attracted to the inner ends of the extended pole pieces. This armature has attached to it a brass stem which extends upwardly through guides, the lower end of this stem serving as a vent valve which, when the armature is attracted by the pole pieces of the horseshoe magnets, closes the ports to atmosphere, and when the armature is released from the magnetic control of the poles, the valve is opened by the air pressure which is constantly applied thereto, thus allowing the main reservoir pressure which is normally held in the chamber of the pneumatic valve, to be released to atmosphere.

Normally the magnet armature is attracted to the upper ends of the extended arms and is held thereon by magnetic attraction which is stronger than the normal air pressure on the face of the valve. When the inductor planes of the affected duplex control valve magnet enter the free field of the track magnet, the polarity of the armature is reversed and the armature is repelled and the air pressure upon the lower face of the valve to which the valve armature is secured, causes the valve to open and thereby actuate the pneumatic valve, which results in the automatic application of the brakes.

Only one of the magneto pneumatic control valves is operated at any one time.

The magnets of the two valves, as heretofore stated, are so arranged as to be of

opposite polarity, that is, the S pole of one and the N pole of the other are in a line parallel to the center line of the track, and all track magnets are installed in the same manner and are of the same polarity. 70

One of the locomotive magnets is therefore always of a polarity opposite to that of the track magnet regardless of the direction the locomotive is headed and also regardless of the position of the track magnet and thus the magnet of the locomotive duplex valve which is of opposite polarity to the track magnet is the one that is the operative locomotive magnet.

As the track magnet is of much greater 80 magnetic strength than the locomotive magnet the polarity of the armature of the operative control valve magnet is reversed due to magnetic induction when the train enters, and as long as it remains in the free field of the track magnet it causes the armature to be released, thereby permitting the vent valve to open which results in the operation of the pneumatic valve.

The advantage of providing duplicate 90 valve structures and duplicate magnetic structures, the latter of which it is to be noted are duplicates save as to their polarity, is not only to permit the operation of the train stop irrespective of the direction in 95 which the train is going, but also irrespective of the position that the track magnet of a block may take when it is installed and also one of the duplicate control valve magnets acts upon the other in the same way 100 that the track magnet acts upon the operative valve magnet so that the field of the operative valve magnet is always at its maximum strength.

Two valve units are provided to ensure 105 that the polarity of at least one will always be opposite that of the track magnet regardless of the direction the locomotive is headed or running and also opposite to the polarity of the track magnet regardless of its 110 position along the rails. The valve equipped with the magnets having a polarity opposite to that of the track magnet is the one that operates and thus only one is operative at any one time. 115

The construction, installation and operation of the magnetic elements of the entire system, both track and train, having been clearly described, reference will now be made to the functioning of the air in the air 120 ducts to produce the desired effects, which ducts are open or closed by the operation of the magnets.

Normally air flows from the main reservoir connection through the pipe 728, 125 through the restricted passageway 510 to the passage 520 into the cylinder head, then past the screw releasing valve stem 308 into the chamber 540. The air also will pass through the port 712 and pipe 130

718 through the passage 604 in the double heading release cock 600 to and through pipe 730 and passages 731 and 732 to vent valve chamber 733. These chambers being closed the main reservoir pressure in the chamber 540 forces the piston 300 upward, closing the brake pipe exhaust valve 310 and opening the puppet valve 140. The pressure of air from the main reservoir also passes from the air passage 732 (Fig. 10) into the passage 737, thence through the safety nipples 725 (Fig. 8) into the safety flange 724 and then into the passages 736. The brake pipe air normally flows from the engineer's brake valve C through the pipe 721 past valve seat 200, chamber 180, chamber 230 into the brake pipe 150.

Assuming that the duplex valve carried on the locomotive is out of the free field of the track magnet, the armatures of the duplex control valve will be held down against the pole piece dowels by magnetic attraction of these duplex control valve magnets. There will be a pressure in the chamber 733, as described above, which exerts itself upward on the end of the valve stem 46, the magnetic attraction on the armature of the duplex valve V being strong enough to hold against this pressure. When the locomotive or railway vehicle carrying the duplex control valve passes over a permanent track magnet and the extending inductor planes of the duplex valve enter the free magnetic field of the track magnet, the polarity of the armature of the magnet of the operative valve in the duplex control valve is reversed due to magnetic induction, the magnetism of the track magnet, as heretofore stated, being of much greater magnetic strength than that of the valve magnets.

This condition remains just so long as the planes are in the free magnetic field of the track magnet, which is a sufficient interval to apply the brakes and stop the train irrespective of the speed of the train. This reversal of polarity causes the armature in the duplex control valve to be released and repelled from the pole piece dowels, thereby permitting the air pressure in the chamber 733 to force the valve stem upward against the valve stem stop 46', and to escape to atmosphere through the ports 735.

The brake pipe pressure in the chamber 230 above the piston 300 together with the spring 320 above the puppet valve 140 and the force of gravity all act to force the piston 300 downward, the spring pressure also forcing the puppet valve 140 down until it seats itself on the seat 200, cutting off communication from the engineer's brake valve C to the brake pipe. The piston continues to travel downward, actuated by the brake pipe pressure and gravity, until it assumes the position shown in Fig. 12, in which position the valve 240 is separated from the

valve seat 310, allowing the brake pipe pressure to flow from the brake pipe 150 through the chambers 723 and 180, ports 230', chamber 230 and ports 420 and 430 to chamber 410, then to the atmosphere at port 330, which result causes an audible sound which may act as a signal.

This operation causes the brake pipe reduction necessary to apply the brakes and the brake pipe exhaust continues until the apparatus is restored to normal position.

After the device is operated and the operative field of the track magnet passed by and the train brought to a stop the double heading lever 606 of the double heading release cock is manually moved (preferably from a position outside of the cab requiring the engineer to dismount therefrom) to released position. This closes the lower plug cock, cutting off communication from the pipe 718 to the pipe 730 and venting any remaining pressure in the chamber 733 to the atmosphere through the port 620 (in the double heading cock) thus relieving the pressure on the end of the valve stem.

The weight of the removable valve stem and nut causes the armature to drop by gravity into the operative field of the valve magnets and the armature is again attracted and restored to normal position and the valve 46 is closed. The lever 606 of the double heading release cock is then returned to running position closing the vent to atmosphere through port 620, and the main reservoir pressure again builds up in the chamber 540 forcing the piston 300 upward, closing the brake pipe exhaust valve 240, forcing the valve stem 210 and puppet valve 140 upward, restoring communication from the engineer's brake valve C to the brake pipe 150.

While the lever 606 is in released position the upper plug cock 607 of the double heading release valve is open, allowing the brake pipe pressure to flow through the double heading cock, through the pipe 714 and thence to atmosphere through the plug 607 of the release valve 600. The lever 606 must be returned to running position for the purpose of closing the exhaust port to this cock, thereby ensuring that the lower cock will be opened and in proper operative position. Failure to do so will leave the brakes still unreleased as the air is exhausting through the pipe 714 and plug cock 607.

The returning of the lever 606 to the running position allows the main reservoir pressure to build up in the chamber 540, forcing the piston 300 up into the chamber 230, closing the valve 240 into its seat 310 and raising the valve 140 off of its seat 200, as above described.

In double heading, all following engines close the air conduit leading from the en-

gineer's automatic control valve, thus preventing the engineer from operating the train brakes. It is also necessary that the train stops on all following engines be made 5 inoperative and the double heading release cock 600 provides this means.

When the handle 606 is placed in released or double heading position, the vent pipe air from the stop to the control valves is cut 10 off and the pipe leading from the engineer's control valve is closed first. Should the engineer fail to place the handle 606 of the cock 600 in double heading release position, the stop will still be operative. Should the 15 engineer fail to place the handle 606 in running position after double heading, his brakes will be applied as soon as he turns the double heading cock to running position because the brake pipe will be vented 20 through the plug cock 607 of the double heading release cock 600.

I provide protection against broken inductor planes in the duplex control valve. These inductor planes P are constructed of 25 cast iron with a port or air passage 736 running lengthwise thereof. If these planes should get broken, air pressure will be exhausted to the atmosphere and bring about the application of the brakes in exactly the 30 same way as if the valve 46 attached to the armature was open in the regular way.

Protection against very strong magnets is provided by reason of the fact that each 35 pair of the duplex magnets are of opposite polarity to each other and therefore, if one pair should become stronger or one weaker than the other, the stronger would act on the weaker the same as the track permanent magnet acts on them.

40 In other words, if one magnet becomes abnormally strong through external means and thereby rendered inoperative, the effect of the weaker magnet on its armature would be neutralized by it and its associated valve operated thereby.

To sum up, the essentials of the operation are:—(1) The permanent track magnet normally provides positive actuation of the automatic stop apparatus on locomotives. 50 Its free magnetic field acts definitely on the control valve pole faces having opposite polarity to its respective poles when such pole faces pass through its free magnetic field. This action causes the valve's magnet armature to be repelled and fall away from the magnet poles, carrying with it the valve-stem, opening the vent valve and thereby causing operation of the pneumatic stop-valve and brake application. (2) The electro magnet control unit, when energized, 55 so diverts and lowers the normal magnetic field of track permanent magnet as to prevent actuation of the apparatus on the locomotive. The solenoid is only energized 60 when trains should be passed in clear.

Thus, the automatic stop operation of brakes is positive when the track conditions would cause an automatic semaphore stop signal and should engineer fail to obey the same.

(3) Upon the automatic service application 70 of the brakes, the engineer can increase to emergency application. He can only release through the operation of the release valve provided. Whether the stop shall be absolute or permissive depends on the location 75 of this release valve, i. e., under or in the cab. In double-heading, the air control being cut from the following engine, the air control cannot be restored to it unless this valve is cut in. (4) No matter what direction 80 the locomotive is heading, one of the magneto pneumatic control valves will be automatically operative since the polarity of one of the two control valves will be opposite to that of track permanent magnet. 85

(5) Air controls the operation of locomotive apparatus and no batteries or electric wiring are used. (6) On the track, only ordinary semaphore maintenance is required.

As changes of construction could be made 90 within the scope of my invention, it is intended that all matter contained in the above description or shown in the accompanying drawings shall be interpreted as illustrative and not in a limiting sense. 95

Having thus described my invention what I claim as new and desire to secure by Letters Patent is:

1. In an automatic train stop device, for use with an air brake system, a plurality of 100 valves, each valve independently controlling the ducts of said system, the opening of either of the valves operating to effect the application of the brakes regardless of the direction of movement of the train, and 105 magnetic means controlling each of said valves, the magnetic means being so conditioned with respect to each other that the polarity of one magnetic means is opposite to the polarity of the other. 110

2. In an automatic train stop device for use with an air brake system, a plurality of valves independently controlling the ducts of said system, and magnetic means for controlling each of said valves, the said magnetic means being so arranged that the north pole of each magnetic means is adjacent to and in line with the south pole of the other whereby the opening of either valve will result in a brake application regardless of the 120 direction of travel of the vehicle.

3. In an automatic train stop device for use with an air brake system, duplicate valves independently controlling the ducts of said system, and magnetic means for controlling each of said valves, the said magnetic means being so arranged that the north pole of each magnetic means is adjacent to and in line with the south pole of the other. 125

4. In an automatic train stop device for 130

use with an air brake system, a plurality of valves for controlling the ducts of said system, magnetic means for controlling each of said valves, the magnetic means being so conditioned with respect to each other that the polarity of one is opposite to the polarity of the other and the field of one magnetic means affects the field of the other, so that should one become abnormally strong through external means and thereby inoperative, the effect of the weaker magnet on its armature would be neutralized by it and its associated valve operated thereby.

5. In combination an automatic train stop device for use with an air brake system, a plurality of valves controlling the ducts of said system, magnetic means controlling each of said valves, the magnetic means being so conditioned with respect to each other that the polarity of one magnetic means is opposite to the polarity of the other, the said magnetic means normally maintaining the valves closed against the fluid pressure in the duct exerted thereupon, and a polarized track magnet of greater power than said magnetic means and through the magnetic field of which each of said magnetic means is movable, said magnetic means being so arranged that a valve is opened and 20 said brake system vented as said magnetic means moves into the field of said track magnet regardless of its direction of movement.

6. In combination, an automatic train stop device for use with an air brake system, a plurality of valves controlling the ducts of said system, magnetic means controlling each of said valves, the magnetic means being so conditioned with respect to each other that the polarity of one magnetic means is opposite to the polarity of the other, the said magnetic means normally maintaining the valves closed against the air pressure in the duct exerted thereupon, and a polarized track magnet of greater power than said magnetic means and through the magnetic field of which each of said magnetic means is movable, the track magnet effecting the release of one of the valves regardless of the 45 position, longitudinally, of the permanent track magnet with respect to the line of track and of the direction of the movement of the train.

7. In combination, an automatic train stop device for use with an air brake system, a valve controlling the ducts of said system, magnetic means controlling the operation of said valve, an inductor plane controlling the magnet of the said valve, the said inductor plane being hollow but normally closed to the atmosphere, an air duct connecting the central hollow portion of the inductor plane with the duct or chamber controlled by said valve, means for connecting the brake pipe with the said air duct,

and means for effecting a reduction of pressure in the brake pipe by venting the air in the inductor plane due to a rupture thereof to effect the application of the brakes.

8. In combination, an automatic train stop device for use with an air brake system, a valve controlling the ducts of said system, magnetic means controlling the operation of said valve, the said magnetic means normally maintaining the valve closed against the air pressure in the air duct exerted thereupon, an inductor plane magnetically connected to said valve, the said inductor plane having a hollow core connected to the air duct controlled by the valve leading to the 70 brake pipe so that upon a rupture of the inductor plane the air in the hollow core thereof vents to atmosphere and pressure in the brake pipe will be reduced to apply the 75 brakes.

9. In an automatic train stop device for use with an air brake system, a plurality of valves controlling the ducts of said system, magnetic means for controlling each of said valves, the said magnetic means being so arranged that the north pole of each magnet of said magnetic means is adjacent to and in line with the south pole of the other and so arranged as to pass through the operative field of the poles of a permanent track magnet, one of the controlling valve magnets acting upon the other in the same way that the track magnet acts upon the operative valve magnet so that the field of the operative valve magnet is always at its maximum 90 strength.

10. A duplex control valve including a casing of non-magnetic metal, at least one permanent magnet mounted therein, pole pieces secured to said magnet, extended cores of high magnetic permeability supporting said pole pieces and secured to said non-magnetic casing, and elongated inductor in planes connected magnetically with said cores and secured to said non-magnetic casing.

11. A duplex control valve including a casing with a chamber formed therein which is open to atmosphere, a magnet having pole pieces secured thereto mounted in said chamber, a valve fitting secured to said casing having ports connecting with said chamber and dowels engaging said pole pieces, an armature normally held in contact with said dowels by said magnet, a valve secured to said armature, a flexible valve seat secured in said fitting and having a restricted port normally closed by said valve and an air duct in said casing whose communication with said chamber is normally cut off by said valve.

12. A control valve structure including a casing having an air duct formed therein, a chamber in the casing having openings to atmosphere, a permanent magnet having ex- 125

tended pole pieces secured to the casing, a valve fitting secured to the casing and connected with said pole-pieces, a valve having guiding means in the fitting, an armature 5 secured to said valve and a valve seat secured in said fitting, the magnet being arranged to normally hold the armature in contact with the pole-pieces so that the communication between said duct and said chamber is normally closed by the valve.

13. A control valve structure including a casing, a chamber formed therein having openings to atmosphere, a nipple having an air duct formed therein, a cap having air 15 passages formed therein secured to the casing and having a body portion extending into the chamber and engaging said nipple, the body having a central chamber therein, a strainer engaging said nipple and secured 20 in said central chamber, the air passages in said cap communicating with said central chamber and a magnetically operated valve normally preventing communication between the air passages in said cap and the chamber 25 which is open to atmosphere.

14. A control valve structure including a casing, a chamber formed therein having openings to atmosphere, a cap having air 30 passages formed therein secured to said casing and having a body portion extending into the chamber, a central chamber formed in said body and communicating with said air passages, a nipple forming an extended air duct from said central chamber, means 35 in said central chamber for straining the air flowing between said air duct and said air passages, a valve controlling the passage of atmospheric air through said air passages to said air duct, a magnet for operating said 40 valve, inductor planes secured to said casing magnetically connected with said magnet and having passages formed therein which communicate with the air passages in said cap so that the breakage or rupture of said 45 inductor planes will vent the said air duct to atmosphere.

15. In an automatic train stop having a plurality of chambers formed therein, a spool shaped piston in one of said chambers 50 having end heads joined by an integral core forming an annular chamber between said heads, a longitudinal port extending from the outer surface of one of the heads part way through the core and having lateral 55 ports connecting with the annular chamber, a valve arranged to close said longitudinal port when the piston is in one position and to open said port when the piston is in another position, means for supplying brake 60 pipe pressure to one head of said piston and main reservoir pressure to the other head of said piston, and a vent to atmosphere communicating with the chamber between said piston heads regardless of its position.

65 16. In an automatic train stop having a

plurality of chambers formed therein, a piston in one of said chambers comprising a pair of outer heads having packing rings in peripheral grooves formed in said heads, a core of smaller diameter than said heads 70 formed integral therewith and having a longitudinal port extending to the outer surface of one of said heads and branch ports extending therefrom to the outer surface of said core.

17. In combination, a train stop having a plurality of chambers therein, a piston in one of said chambers, means for supplying brake-pipe pressure to a chamber on one side of said piston and means for supplying 80 main reservoir pressure to a chamber on the other side of said piston, a pipe leading from the last mentioned chamber to a normally closed magnetically operated valve capable of venting the pressure in said last 85 mentioned chamber to atmosphere, a double heading valve in said pipe having a double-valve plug with a port normally permitting the pressure to flow through said pipe, a second pipe connected to said double heading 90 valve and connected with the brake pipe below the engineer's control valve, a passage in said double heading valve leading to atmosphere and a second port in said double valve plug so positioned with respect to the 95 other port that when said valve plug is turned to stop the flow of pressure through the first mentioned pipe the second port will be positioned to vent the pressure in the second pipe through said passage in the valve 100 leading to atmosphere.

18. A train stop having a movable piston therein operated by differential pressures for venting the brake pipe pressure to atmosphere, chambers on each side of said piston, 105 means for supplying brake pipe pressure to the chamber on one side of said piston and main-reservoir pressure to the chamber on the opposite side of said piston, an air passage in said piston and a valve for closing 110 communication between said passage and the chamber which is supplied with brake pipe pressure, a cap secured to the train stop having a duct for main reservoir pressure, and means for manually moving said piston 115 to cause said valve to close the air passage in the piston and also to prevent the passage of pressure from said duct to the chamber adjacent the piston.

19. A train stop having a movable piston 120 therein, operated by differential pressures for venting the brake pipe pressure to atmosphere, chambers on each side of said piston, means for supplying brake pipe pressure to the chamber on one side of said piston and main-reservoir pressure to the chamber on the opposite side of said piston, an air passage in said piston and a valve for closing communication between said passage 125 and the chamber which is supplied with 130

brake pipe pressure, a cap secured to the train stop having a duct for main reservoir pressure, and a revolvable nut, a threaded shank coacting therewith having an extension for moving said piston to cause said valve to close the air passage in the piston, and a valve for closing communication between said duct and the chamber adjacent the piston.

- 10 20. In an automatic train stop device for use with an air brake system, a plurality of valves independently controlling the ducts of said system, magnetic means controlling each of said valves, one of said magnetic means having its polarity arranged opposite to the polarity of the other, and unitary means external to the magnetic controlling means to obtain a selective action for opposite train movement.
- 15 21. In an automatic train stop mechanism for use with an air brake system having a main pipe and a brake pipe, a cut-off valve between said main pipe and said brake pipe, a magnetically controlled vent valve, a passage from said main pipe to said vent valve, and a piston arranged to control said cut-off valve and to close said passage when said vent valve is opened.
- 20 22. In an automatic train stop mechanism for use with an air brake system having a main pipe and a brake pipe, a cut-off valve between said main pipe and said brake pipe, an automatically controlled vent valve, a plate having an orifice, a passage from one 25 side of said orifice to said main pipe, a passage from the other side of said orifice to said vent valve, a piston arranged to control said cut-off valve, and means to manually raise the piston and to close communication through said orifice.
- 30 23. In an automatic train stop mechanism for use with an air brake system having a main pipe and a brake pipe, a cut-off valve between said main pipe and said brake pipe, a piston arranged to operate said cut-off valve, an automatic vent valve for controlling said piston and a manually operated means for opening said cut-off valve and stopping the passage of air to said vent 35 valve.
- 40 24. In an automatic train stop mechanism

for use with an air brake system, having a main pipe and a brake pipe, a cut-off valve between said main pipe and said brake pipe, automatically controlled vent valve 55 for closing said cut-off valve when said vent valve is opened and manually operable means for opening said cut-off valve and stopping the passage of air to said vent valve.

60 25. In an apparatus of the class described, a control valve unit structure comprising a casing of non-magnetic material, longitudinally extending inductor planes secured thereto, transversely extending magnet 65 cores secured to said casing and connected to said inductor planes, a permanent magnet carried by said cores, and a valve operatively associated with said permanent magnet.

70 26. In an apparatus of the class described, a control valve unit structure comprising a casing of non-magnetic material, longitudinally extending inductor planes secured thereto, transversely extending magnet 75 cores secured to said casing and connected to said inductor planes, a permanent magnet carried by said cores, air ducts formed in said control valve unit, an armature adapted to coact with said magnet, and a valve carried by said armature arranged to control the passage of pressure fluid through said ducts.

75 27. In an apparatus of the class described, a control valve unit structure comprising a 85 casing of non-magnetic material, longitudinally extending inductor planes secured thereto, transversely extending magnet cores secured to said casing and connected to said inductor planes, pole pieces secured 90 to said cores, a permanent magnet secured to said pole pieces, a valve bushing, guiding means carried by said bushing, an armature coacting with said guiding means and associated with said pole pieces and a valve 95 secured to said armature.

In witness whereof I have hereunto set my hand at Mill Valley, county of Marin, State of California, this 18th day of October, 1920.

HOWARD S. FOLKER.
